United States Patent Office

Des. 183,599
Patented Sept. 30, 1958

183,599

RAILWAY PASSENGER CAR

Walter B. Dean, Narberth, and Richard M. Irwin, Philadelphia, Pa., assignors to The Budd Company, Philadelphia, Pa., a corporation of Pennsylvania

Application January 29, 1957, Serial No. 44,651

Term of patent 14 years

(Cl. D66—1)

Des. 183,599

PAGE 2

正.乙.

Fig. 1 is a perspective view looking from the front end at the line 1—1 of Figure 4;

Fig. 2 is a perspective view looking from the rear end at the line 2—2 of Figure 4;

Fig. 3 is a transverse sectional view in outline;

Fig. 4 is a vertical longitudinal sectional view in outline; and

Fig. 5 is a side elevational view of a railway passenger car, embodying our new design.

The dominant features of our design reside in those portions shown in full lines.

We claim:

The ornamental design for a railway passenger car, substantially as shown and described.
